S. ROESNER.

FLASH LIGHT APPARATUS FOR PHOTOGRAPHIC PURPOSES.

APPLICATION FILED FEB. 27, 1909.

927,876.

Patented July 13, 1909.

UNITED STATES PATENT OFFICE.

SIEGMUND ROESNER, OF CHICAGO, ILLINOIS.

FLASH-LIGHT APPARATUS FOR PHOTOGRAPHIC PURPOSES.

No. 927,876.

Specification of Letters Patent.

Patented July 18, 1909.

Application filed February 27, 1909. Serial No. 480,471.

To all whom it may concern:

Be it known that I, SIEGMUND ROESNER, a subject of the Emperor of Russia, (who have announced my intention of becoming a citizen of the United States,) residing at Chicago, in the county of Cook and State of Illinois, have invented certain new and useful Improvements in Flash-Light Apparatus for Photographic Purposes, of which the following is a specification.

This invention relates to improvements in flash-light devices for use in photography, the chief object of the invention being to provide a device whereby a charge of flash-light powder can be ignited through the agency of an ordinary match by the operator at a greater or less distance from the device.

The device is preferably provided with means for attaching it to and supporting it by the camera with capacity for universal angular adjustment, as well as bodily adjustment toward and from the camera, so that the charge of powder may be suitably positioned to produce the desired lighting effect upon the person or object being photographed.

The invention will be readily understood when considered in connection with the accompanying drawings, wherein I have shown one practical embodiment thereof, and referring thereto,—Figure 1 is a top plan view of the device. Fig. 2 is a side elevation, broken out between its ends. Fig. 3 is a detail view, in longitudinal section, through one member of the pneumatically operated detent of the match-holder. Fig. 4 is a detail sectional view through one of the universal joints of the supporting standard of the device; and Fig. 5 is a detail in cross-section through a slightly modified form of match-scratching bar.

Referring to the drawing, 10 designates as an entirety a base-plate, one end of which, 11, constitutes a powder-pan adapted to support a charge of flash powder shown at 12, and preferably equipped with rear and side walls 13 and 14 constituting a shield or guard in those directions in which the lighting effect of the powder is not required. Secured to the upper surface of the plate 10 is a metal strip 15, the ends of which are turned upwardly and apertured to form bearings 16 for a shaft or drum 17, this latter being provided with reduced ends or pintles 18 rotatably mounted in the bearings 16. The shaft or drum 17 is equipped with

a hollow radially disposed tube 19 in which may be inserted the stem of an ordinary match 20; the drum 17 and tube 19 thus constituting a match-holder or carrier. The 60 said match-holder is normally impelled to turn in a direction to carry the match over toward the powder-pan by means of a torsion spring 21 that is coiled around the drum 17, one end thereof being anchored at 22 in 65 the bearing member 16, while the other end, shown at 23, hooks beneath the inner portion of a radial detent arm 24 secured to said drum.

Soldered or otherwise suitably secured beneath and across the end of the base-plate 10 opposite that which forms the powder pan is a cylinder 25, shown in detail in Fig. 3, equipped at one end with a nipple 26 adapted for ready attachment thereto of an 70 air-hose 27 operated by the usual hand bulb 28. Slidably mounted in the cylinder 25 is a plunger 29, in the outer projecting end of which is a hook or catch 30 projecting upwardly through a slot 31 in the base-plate 75 10 and adapted to engage and hold the free end of the detent arm 24 of the match-holder against the torsional effort of the spring 21.

Secured to the same end of the base-plate 10, above the cylinder 25, is an upright supporting bracket 32, to the upper end of which is hinged at 33 one end of a curved scratcher-bar 34, the opposite or free end of which latter normally overhangs the powder-pan. This scratcher-bar is provided on its 80 under side with a roughened surface, herein shown as a strip of sandpaper 35 suitably secured thereto; and said scratcher-bar is so located as to lie substantially coincident with or slightly below the path of travel of 85 the head of the match 20, so that, when the detent arm 24 is released, which is done by compressing the bulb 28 and thus shifting the plunger 29 outwardly to release the catch 30 from the detent arm, the head of the 90 match rubs over the roughened under surface of the scratcher-bar, slightly raising the latter on its pivot, the weight of the bar insuring a sufficient frictional contact to ignite the match. The match, when thus ignited, 95 is thrown with its ignited head into or closely adjacent to the charge of powder, so that the latter is readily set off.

While the device as thus far described is complete and operative for the principal 100 purpose of the invention, and may be mounted or supported in any suitable way or by

any convenient means, yet it is desirable to provide means whereby it may be attached directly to the camera itself, with capacity for properly positioning the powder-pan to give the desired lighting effect upon the subject. For this purpose I provide a universally adjustable support, consisting, as herein shown, of the following parts.

A tube 36 and a rod 37 telescoping the same constitute an extensible standard, said parts being provided at their outer ends with rigid spherical knobs or balls 38, and frictionally held in any longitudinally adjusted position as by means of a spring tongue 39 formed in the tube 36 by slitting the metal on either side of said tongue and bending the latter inwardly. Each of the knobs 38 engages a hollow longitudinally split and externally threaded boss 40, shown in detail in Fig. 4, adapted to be compressed into gripping engagement with said knob by a nut 41. One of these hollow bosses is secured to the under side of the base-plate 10, while the other is formed on the upper end of a screw 42, which latter has threaded engagement with the upper arm of a clamp-member 43 adapted to engage over the front edge of the top horizontal wall of an open camera case or box, the screw 42 having on its lower end a head 44 constituting the upper member of the clamp. The ball joints shown at the upper and lower ends of the extensible standard are both universal angular joints; so that the powder-pan can readily be adjusted to any desired angular position, as well as on any side of the camera, to produce the best lighting effect, while its distance from the camera can be regulated by the extensible support.

In Fig. 5 I have shown a slightly modified form of match-scratcher bar, consisting of a bar 34^a of substantially V-form in cross-section, so that the head of the match as it rubs the same, engages the roughened friction surface on two of its sides, rather than simply on its tip, as in the form shown in Figs. 1 and 2. This last-described form of scratcher-bar is best adapted for ordinary matches having heads of a single composition, while the form shown in Figs. 1 and 2 is best adapted for a type of match now extensively used that is provided with a special ignition tip designed to prevent the flying of burning particles of the head when the match is scratched.

I am aware that flash light devices adapted to be operated at a distance through the ignition of the charge by electric means, and by the firing of a cap through the agency of a spring-actuated hammer, are old, as also the ignition of a charge through the release of a spring-actuated sweep having a roughened surface adapted to rub over the heads of one or more stationary fuses surrounded by a charge of powder. So far as I am

aware, however, my present invention is broadly novel in the employment of a spring-actuated device adapted to hold a match and rub the latter over a striker-bar to ignite it in such a manner as to bring the head of the match, when ignited, into juxtaposition to a charge of powder. Hence, while I have shown and described what I believe to be the best and most practicable form of my invention, yet it should be understood that the same may be varied and modified to a considerable extent in respect to details without involving any departure from the principle of the invention or sacrificing any of its advantages. 80

I claim:

1. In a flash-light apparatus, the combination with a powder-pan, of a rotary spring-actuated match-holder adapted to support a match radially thereof, a detent for said match-holder, a curved gravity scratcher-bar having a roughened under surface overlying said match-holder, said scratcher being pivotally supported at one end with its free end overhanging said powder-pan, and means for releasing said detent, substantially as described. 85

2. In a flash-light attachment for cameras, the combination with a base-plate formed at one end to constitute a powder-pan, of a spring-actuated match-holder rotatably mounted above said base-plate and provided with a radial support for a match, a radial detent arm carried by said match-holder, a pneumatically operated catch for said detent 100 arm mounted on the opposite end of said base-plate from said powder-pan, a supporting bracket mounted on said base-plate, a curved scratcher-bar having a roughened under surface hinged at one end to said supporting bracket with its free end overlying said powder-pan, and an angularly adjustable support for said base-plate adapted to be attached to a camera, substantially as described. 105

3. In a flash-light apparatus, the combination with a base-plate formed at one end to constitute a powder-pan, of a match-holder journaled above said base-plate and comprising a spring-actuated shaft and a hollow 115 radially disposed tube thereon adapted for the insertion of the stem of a match, a pivoted gravity scratcher-bar disposed above and transversely of said shaft, a detent for holding the shaft of said match-holder 120 against the tension of its actuating spring, and means for releasing said detent, substantially as described.

4. In a flash-light apparatus, the combination with a base-plate formed at one end to 125 constitute a powder-pan, of a match-holder journaled above and across said base-plate and comprising a spring-actuated shaft and a hollow radially disposed tube thereon adapted for the insertion of the stem of a match, 130

a bracket on said base-plate, a scratcher-bar having a roughened concave under surface pivoted at one end to said bracket and overlying said match-holder, the free end of said scratcher bar overhanging said powder-pan, a detent for holding the shaft of said match-holder against the tension of its actuating

5 spring, and means for releasing said detent, substantially as described.

SIEGMUND ROESNER.
